P. TRIEBEL

REGISTER FOR COAL CARS OR THE LIKE

Filed Oct. 3, 1922

Fig. 6,

INVENTOR
Paul Triebel
BY
Max. Ordmann
ATTORNEY

UNITED STATES PATENT OFFICE.

PAUL TRIEBEL, OF JERSEY CITY, NEW JERSEY.

REGISTER FOR COAL CARS OR THE LIKE.

Application filed October 3, 1922. Serial No. 592,002.

To all whom it may concern:

Be it known that I, PAUL TRIEBEL, a citizen of the United States of America, residing at Jersey City, in the county of Hudson and State of New Jersey, have invented certain new and useful Improvements in Registers for Coal Cars or the like, of which the following is a specification.

This invention relates to indicating or 10 numbering devices for marking receptacles or cars, such, for instance, as coal or ore cars used in mines. Particularly with coal cars my device is of great advantage.

To indicate the car loaded by a particular 15 miner it has heretofore been customary to number the car by chalk or other means with the number of the miner. Such mark can, however, be easily wiped out and changed for another number, in which case not only 20 does the miner who loaded the car lose his pay, but the mine owner would have no record of the one who made the change.

The object of this invention is to construct a simple and effective device to be applied to 25 the car or the like, whereby a number, once set, cannot be changed while the receptacle or car is loaded, but which will permit the change of the number or mark only after the car has been unloaded or while the latter is 30 empty.

To this end my device consists of adjustable marking or numbering mechanism which automatically becomes locked in position by the load or the contents of the car 35 or receptacle.

My invention will be more fully understood by reference to the accompanying drawing in which similar reference characters denote corresponding parts and in 40 which Fig. 1 is a sectional elevation of a coal car equipped with my device; Fig. 2 a rear elevation of the lid or cover of the casing; Fig. 3 is a central cross section of the device proper; Fig. 4 is a longitudinal section on line 4-4 of Fig. 3; Fig. 5 is a front elevation of a modified construction of the device partly in section; Fig. 6 is a cross section thereof and Fig. 7 is a similar section to Fig. 6 showing a modification of a detail.

Let *a* denote a miner's car of usual construction. My device is adapted to be permanently fixed to one of the walls of the car and comprises in its simplest form a box shaped casing 10, the front wall 11 of 50 which is entirely removable and in closed position fits in the box so that its front face

is about flush with the edges of the side walls of the box.

Fixed to and projecting from the inner face of the front wall 11 are horizontal 60 brackets 12 which carry a longitudinally extending axle 13. On this axle are rotatably mounted a plurality of dial disks 14 preferably of polygonal shape, on the faces of which are printed or otherwise applied figures or numbers 15 from "0" to "9." The wall 11 has windows or openings 11' through which the figures or numbers, one at a time, are visible from the front face of the disks. These disks are displaceable longitudinally 70 on said axle, but normally are adapted to be held endwise close to one another through a spring 16 mounted on the axle 13, and to be locked in adjusted position through pins 16', of which one projects from one of the brackets 12 and one from one end face of a disk, and each of which is adapted, after adjustment of the disks, to engage one of a circular series of notches 17 provided in the opposite end faces of the disks. 80

These locking means serve to prevent an accidental displacement of the dial disks during adjustment and prior to the insertion of the wall 11 into the casing 10.

To safeguard against forcible displacement of the dial disks when attempts are made to change the figures by insertion of an instrument through the openings 11' of the front wall 11, the polygonal disks are so arranged or made of such a diameter, that 90 when the wall 11 is put into closing position, one of the faces of each of the polygonal disks will bear against the inner face of the rear wall of the casing, as shown in Fig. 4, and become thereby locked. 95

Fixed to and projecting rearwardly from the lower part of the inner face of the wall 11 is a lug 18 preferably of square cross section which in length is so admeasured that when the cover is placed into closing position, it will project through a correspondingly shaped opening *a'* of the wall of the car to which the device is fixed, and its free end will terminate near the inner face of said wall. Hinged or otherwise pivotally 100 secured to the free end of said lug, as at 19, is an arm 20 so as to swing vertically. This arm is so dimensioned that in horizontal position it will freely pass thru the opening *a'* of the wall of the car and when swung 105 downwardly it will terminate near the bottom of the car. In this downwardly swung 110

position the arm serves as a lock for the cover 11 holding the latter in closing position and prevent access to the dial disks. The arm will be retained in its locking position by the load or contents *x* of the car. When the car is empty the arm can be lifted into horizontal position to permit the removal of the cover so that the numbers may be changed when desired or necessary *re-10* pairs made.

In the modification shown in Figs. 5 and 6, the cover 11 has riveted or otherwise secured to it inwardly projecting horizontal axles 21 on which are rotatably mounted *15* the polygonal dial disks 22, so as to be parallel to the wall 11. These disks are adapted to bear against washers or collars 23 provided on the axles 21 and to be held in position by plate springs 24 which are fixed to *20* the axles 21 by screw bolts 25. Each of these dial disks has printed on or otherwise applied to its front face a circular series of figures 26 from "0" to "9" of which one at a time may be made visible thru the window *25* or opening 11' of the cover 11. The springs 24 may each be formed with round projections 24' to cooperate with a circular series of impressions or notches 22' provided on the inner face of each dial disk, one opposite each *30* figure. These projections 24' cooperating each with a depression or notch 22' of a dial disk hold the latter from accidental displacement from its adjusted position.

10' denote reinforcing members and *102* *35* ribs, the front edges of which act as bearings for the inner face of the cover or front wall 11.

The dial disks are so arranged that the edge of any one side of each dial disk when *40* in horizontal position and after the cover or front wall has been placed into closing position, will bear against the inner face of the upper or lower wall of the casing according to the location of the particular *45* dial disk. Thus, the lateral or end disks will bear on the lower inner wall and the intermediate dial disk on the upper wall of the casing. A movement of the dial disk from the outside without the removal of the front *50* wall is, therefore, rendered entirely impossible.

One of the main advantages of this construction is that in case any one of the dial disks or other parts require repair, the cover *55* 11 can be removed and another one substituted in its stead.

In order to hold the arm in locking position or from swinging during the evacuation of the car or receptacle, an auxiliary locking device, such as shown in Fig. 7,

may be used. This device comprises a spring member 27 fixed to the free end of the arm 20 and adapted, when the arm is turned downwardly, to snap over a projection 28 provided on the bottom of the car.

65

It is, of course, understood that various other modifications may be made in the construction of the device without deviating from the principle of my invention. I, therefore, do not wish to restrict myself to *70* the details of the construction described and shown.

What I claim is:—

1. The combination with a receptacle, of a marking or numbering device, comprising *75* a casing adapted to be fixed to said receptacle and having a removable wall, adjustable dial members supported in said casing and means pivoted to said wall and adapted to be acted upon by the contents of the receptacle to prevent access to said dial members.

2. The combination with a receptacle, of a marking or numbering device, comprising a casing adapted to be fixed to said receptacle and having a removable wall, adjustable dial disks supported in said casing and a tiltable member pivoted to said removable wall and adapted in tilted position to lock said wall in closing position, said tiltable member being automatically retained in *80* locking position by the contents of the car.

3. The combination with a miner's car, of a marking or numbering device, comprising a casing fixed to said car, a removable cover to close said casing having openings, dial *85* disks rotatably mounted on the inner face of said cover, the figures of each disk being visible, one at a time, through said openings, and a vertically tiltable member pivoted to said cover and adapted to project *90* into the car, said member being adapted when tilted downwardly to lock said cover in closing position and to be retained in locking position by the contents of the car.

4. The combination with a miner's car, of *95* a marking or numbering device, comprising a casing fixed to said car, a removable cover for said casing, numbering dials on said cover and gravity actuated means pivoted to said cover and serving to lock the latter *100* in closing position, said gravity actuated means being adapted to be locked in locking position by the contents of the car.

In testimony whereof I affix my signature in presence of two witnesses.

PAUL TRIEBEL.
